UNITED STATES PATENT OFFICE.

DAVID L. SUMMEY, OF WATERBURY, CONNECTICUT, ASSIGNOR TO SCOVILL MANUFACTURING COMPANY, OF WATERBURY, CONNECTICUT, A CORPORATION OF CONNECTICUT.

ART OF FURNACE LINING.

Application filed October 1, 1926. Serial No. 138,858.

This invention relates to the art of furnace lining.

In a known type of induction furnace which may be cited as an example, an interior channel or passage, usually roughly V-shaped, communicates at its two ends with the hearth of the furnace. This channel receives a portion of the molten bath which acts as the secondary of the transformer and the molten metal is circulated through the channel, thereby establishing a circulation of the bath for the effective transmission of heat to the charge. Such a furnace is shown in U. S. patent to James

15 R. Wyatt, No. 1,201,671.

The channel referred to, because of the high temperatures involved, is bounded by refractory material. According to known practice, the channel is formed by tamping refractory material around a templet or pattern of the shape of the desired channel, allowing the refractory material to set, and removing or destroying the templet by means of heat. If expansion of the templet, under

20 25 the application of heat, is not prevented, the surface of the refractory lining is liable to be cracked or otherwise injured by such expansion.

It is an object of the present invention to provide a method of and means for manufacturing furnace linings effectively and economically, avoiding injury to the lining by expansion of the form.

With this general object, and others, in view, the invention consists in the features, combinations, details of construction and arrangements of parts which will first be described in connection with the accompanying drawing and then more particularly pointed out.

In the drawing;

Figure 1 is a vertical sectional view through an induction furnace with a form therein constructed in accordance with the invention;

Figure 2 is a top plan view (enlarged) of the form itself;

Figure 3 is a sectional view taken on the line 3—3 of Fig. 2;

50 Figure 4 is an edge view of the form with parts in vertical section; and,

Figure 5 is a sectional view (enlarged) taken on the line 5—5 of Fig. 3.

Referring to the drawing, the furnace il-

lustrated as an example comprises a furnace body 11 formed of firebrick or other suitable material and enclosed in a metal casing 12. Within the body is a furnace lining 13 of suitable refractory material. The furnace has a pouring spout 14 and a charging door 15 communicating with the hearth 16. Communicating with the lower part of the hearth are the two ends of a substantially V-shaped channel indicated at 17. This channel is bounded by the refractory lining 13, the outer defining surfaces merging into the straight walls of the hearth and the inner surfaces merging into a rounded hearth bottom, as shown in Fig. 1.

Surrounding the upper ends of the channel is the core 18 of a transformer with a primary coil suitably wound and connected, the inner leg of the core and the primary coil being encased in a shell 19. When the furnace is in operation the molten metal in the channel acts as the transformer secondary.

The lower part of the furnace lining, that is, the part which bounds the channel, is formed by tamping refractory material about a templet and removing the templet after the refractory material has properly set. While various refractory materials having various consistencies may be used, a dampened granular material having a consistency somewhat like damp sand has been found suitable.

According to the present invention, there is provided a templet or form having substantially the shape of the channel to be formed, destructible by heat, and capacitated to be rendered collapsible in the initial heating period. This may be accomplished, for example, by providing the templet with a relatively weak or low heat-resisting portion following a given line around the periphery of the templet and, in effect, connecting two halves separated by a plane longitudinal of the furnace. The templet may conveniently be constructed of wood as such a templet is easy to build and easy to burn out. In such cases, the weak portion may be a relatively thin wall so arranged that when the templet is heated up to the point of combustion, the material of the thin wall is consumed first, i. e., during a preliminary combustion period. This destruction of the dividing wall separates the templet into two

parts collapsible, one toward the other, thereby to take up or compensate for any tendency of the wood to expand during the main combustion period.

5 While the templet may vary in construction, in the embodiment here illustrated as an example, it comprises a V-shaped wooden frame or form 20, the legs of the V being connected at the top by two spaced straps 10 21 which define a groove at the bottom of the furnace pool. The outer edges of the V merge into straight lines corresponding to the sides of the hearth, as appears in Fig. 1. The inner edges of the V merge into a 15 curve which is continued by the bottom edges of the straps 21, this curve corresponding to the rounded portion of the furnace bottom at the bottom of the hearth. The whole frame is somewhat the shape of 20 an inverted stirrup, as appears in Fig. 3, and may be made up of such separate pieces, assembled and connected together, as may be desired.

The form 20 has a weak heat-resisting 25 portion designed for early combustion. As here shown as an example, extending through the V and up to the top of the form is a cylindrical channel or bore 22. This bore is so dimensioned that at the longitudinal lines where the bore most closely approaches a tangential relation with the faces 23, 24, of the form, there is left a relatively thin double wall 25, strong enough to hold the templet rigid under tamping 30 pressure but thin enough to burn through easily. This wall runs around the V, including the straight extensions, in a line, or rather a strip, located substantially midway of the end edges 26, 27 of the form and thus, 35 in effect, connects two form halves separated by a longitudinal plane.

In the embodiment illustrated, the bore 22 serves also as a conduit for a resistor strip or wire 28 which is threaded through the 40 bore and has its ends extending outwardly at the top (Fig. 3) for connection in a suitable circuit.

At opposite sides of bore 22 are other channels or bores 29, 30, for the passage of 45 an air or oxygen blast to aid combustion.

In use, the templet is suitably positioned and the refractory material is tamped about the same to form the furnace lining. During this tamping the form is rigid and within 50 stands tamping pressure so as to constitute a proper pattern for the channel desired. After a proper setting period, the resistor strip 28 is connected in circuit and the heat set up therein heats the wooden form to the 55 point of combustion. Owing to the fact that the double wall 25 is relatively thin and weak and is near the source of heat, it burns through during the initial stages of combustion. This, in effect, separates the 60 form into two longitudinal parallel parts 65

collapsible one toward the other. This separation takes place before the form as a whole heats up sufficiently to exert any substantial expanding pressure on the furnace lining. As a result, the tendency to expand 70 is taken up by the collapse or inward movement of the separated form parts and injury to the lining is avoided. By continued combustion, which may be aided by an air blast, the form is destroyed and the furnace 75 channel made ready for use.

What is claimed is:

1. A templet for the purpose described, providing a pattern having substantially the shape of the channel to be formed and 80 capacitated to be destroyed by the application of heat, and having a portion running longitudinally around the templet between the end edges and capacitated to be destroyed by heat relatively rapidly with respect to the pattern as a whole, whereby upon application of heat the templet is relatively early divided into two parts movable one toward the other. 85

2. A templet for the purpose described, 90 composed of wood and providing a pattern having substantially the shape of the channel to be formed, and having a portion extending around the body of the templet between the edges thereof and arranged, upon combustion, to burn out relatively rapidly with respect to the combustion of the form at large, thereby to divide the templet into 95 two parts movable one toward the other prior to the major combustion. 100

3. A templet for the purpose described, composed of wood and providing a pattern having substantially the shape of the channel to be formed, and having, substantially 105 midway of its end edges, relatively thin portions in the inner and outer walls, whereby upon combustion such thin portions burn out relatively rapidly with respect to the combustion of the pattern at large, thereby to divide the templet into two parts movable one toward the other prior to the major combustion. 110

4. A templet for the purpose described, composed of wood and providing a pattern 115 having substantially the shape of the channel to be formed, and having substantially midway of its end edges a bore running around the body of the templet and forming relatively thin portions in the inner and outer walls, whereby upon combustion such thin portions burn out relatively rapidly with respect to the combustion of the pattern at large, thereby to divide the templet into two parts movable one toward the other prior to the major combustion. 120

5. A templet for the purpose described, composed of wood and providing a pattern having substantially the shape of the channel to be formed, and having substantially 125 midway of its end edges a bore running 130

- around the body of the templet and forming relatively thin portions in the inner and outer walls, whereby upon combustion such thin portions will burn out relatively rapidly with respect to the combustion of the pattern at large, thereby to divide the templet into two parts movable one toward the other, and supplemental bores on either side of said first named bore.
- 10 6. The method of making the refractory structure of an electric furnace having an interior channel, which comprises forming a pattern having the shape of the channel to be formed, tamping refractory material about said pattern, causing a portion of said pattern, in a dividing strip running longitudinally around the body thereof, to be destroyed, whereby the pattern is divided into two portions movable one toward the other, and destroying the remainder of the pattern.
- 15 7. The method of making the refractory structure of an electric furnace having an interior channel, which comprises forming a pattern having the shape of the channel to be formed and having a bore running longitudinally around the pattern to form relatively thin side wall portions substantially midway of the ends, tamping refractory material about said pattern, applying heat to the pattern to burn through said wall portions, whereby the pattern is divided into two portions movable one toward the other, and further supplying heat to burn the remainder of the pattern.
- 30 35 In testimony whereof, I have hereunto set my hand.

DAVID L. SUMMEY.
